UNITED STATES PATENT OFFICE.

HORACE SHEBLE AND THOMAS KRAEMER, OF PHILADELPHIA, PENNSYLVANIA,
ASSIGNORS TO DOMESTIC TALKING MACHINE CORPORATION, OF PHILADEL-
PHIA, PENNSYLVANIA, A CORPORATION OF PENNSYLVANIA.

SUPPORT FOR THE SOUND-BOXES OF TALKING-MACHINES.

1,280,565.

Specification of Letters Patent.

Patented Oct. 1, 1913.

Application filed July 7, 1916. Serial No. 107,936.

To all whom it may concern:

Be it known that we, HORACE SHEBLE and THOMAS KRAEMER, both citizens of the United States, residing in Philadelphia, Pennsylvania, have invented certain Improvements in Supports for the Sound-Boxes of Talking-Machines, of which the following is a specification:

The object of our invention is to provide simple and effective means whereby the sound box of a phonograph instrument can be so mounted upon the tone arm as to be readily changed from position for use in connection with records of the "lateral wave" type to position for use in connection with records of the vertical cut or "hill-and-valley" type, the sound box when in either position being so locked to the tone arm as to prevent displacement of the sound box from its proper relation to the record.

This object we attain in the manner hereinafter set forth, reference being had to the accompanying drawings, in which—

Figure 1 is a side elevation of the sound box of a phonograph and part of the tone arm employed in connection therewith, illustrating our invention and showing the parts in position for use in connection with a record of the lateral wave type;

Fig. 2 is a side elevation showing the sound box and tone arm in position for use in connection with a record of the vertical cut or hill-and-valley type;

Fig. 3 is a transverse section on the line 3—3, Fig. 1;

Fig. 4 is a transverse section on the line 4—4, Fig. 2;

Fig. 5 is a perspective view of that member of the tone arm which engages with the sound box member; and

Figs. 6 and 7 are horizontal sectional views in different positions of sound box and tone arm members illustrating a modification of our invention.

Referring in the first instance to the construction shown in Figs. 1 to 5 of the drawing, 1 represents the sound box casing and 2 part of the tone arm upon the end of which said sound box is mounted. Both of these parts may, except as to their engaging members, vary in construction without affecting our invention, the latter being concerned only with said engaging members and being intended to insure the rigid mounting of the

sound box on the tone arm in either of the two positions required, the ready shifting of the sound box from one position to the other, and its accurate location in either position.

In the device shown in Figs. 1 to 5 that end of the tone arm 2 which is adjacent to the sound box 1 is provided with a tubular head 5 having a tubular flange 6 projecting therefrom into the end of the tone arm and suitably secured within the latter. Projecting downwardly and forwardly from the head 5 is a hollow elbow 7 preferably of rectangular cross section and the downwardly projecting arm of said elbow fits snugly into a pocket 8 on the back of the sound box and either formed in one piece therewith or rigidly secured thereto in any available manner.

The lower end of the downwardly projecting arm of the elbow 7 extends to the bottom of the pocket 8 but is partially cut away, as shown in Fig. 5, so as to present but two sides 9—9 at right angles to one another, and, as shown in Fig. 3, that portion of the pocket 8 which corresponds to this cut away portion of the elbow 7 communicates through a curved neck 10 with the aperture in the back of the sound box through which the sound waves pass, and, by way of said curved neck 10 and the elbow 7, are directed to the tone arm 2.

When the sound box is adjusted for use in connection with a lateral wave groove, it occupies a plane parallel with that of the tone arm and lies alongside of the elbow 7, as shown in Figs. 1 and 3, but when the sound box is to operate in connection with a record of the hill-and-valley type it occupies a forwardly inclined plane substantially at right angles to the axis of the tone arm 2, and lies along the outer face of the elbow 7, as shown in Figs. 2 and 4. The sound box can be readily changed from one position to the other by simply slipping the pocket 8 from the elbow 7, turning the sound box one-quarter way around and reapplying the pocket to the elbow in the new position.

By preference, the sound box, after being adjusted to the proper vertical position, is secured in such position in any suitable way, as for instance by means of a set screw 11 engaging a threaded boss on the back of the

pocket 8 and bearing against the rear face of the elbow 7, as shown in Fig. 2.

In the construction shown in Figs. 1 to 4 the pocket 8 and elbow 7 occupy a position 5 at one side of the center of the sound box but this is not essential to our invention, nor is it necessary that the pocket and elbow shall be of rectangular cross section, so long as their engagement is a nonrotatable one.

10 In Figs. 6 and 7 we have shown a construction in which, the elbow 7^b has on one side a projecting lug 12^a and the pocket 8^b has grooved ribs 14^a in planes at right angles to one another, one of these ribs 15 engaging the lug 12^a when the sound box is in one position, as shown in Fig. 6, and the other when the sound box is in the other position, as shown in Fig. 7.

We claim:—

20 1. The combination, in a phonograph instrument, of a tone arm having at the end an elbow member with downwardly projecting arm with a sound box having a member

in engagement with said downwardly projecting arm, said engaging members having 25 a cross sectional form which prevents rotation of one in respect to the other until they have been disengaged lengthwise.

2. The combination, in a phonograph instrument, of a tone arm having at the end 30 an elbow member with downwardly projecting arm of rectangular cross section, with a sound box having a member with rectangular walls fitted to said downwardly projecting arm of said elbow member whereby said 35 parts are retained in non-rotatable engagement until they have been disengaged lengthwise.

In testimony whereof, we have signed our names to this specification, in the presence 40 of two subscribing witnesses.

HORACE SHEBLE.
THOMAS KRAEMER.
